Patented May 14, 1918.

FIG. 1.

FIG. 2.

INVENTOR,
Bertie H. Urschel
By Marion Hall, Atty.

UNITED STATES PATENT OFFICE.

BERTIS H. URSCHEL, OF BOWLING GREEN, OHIO, ASSIGNOR TO THE UNIVERSAL MACHINE COMPANY, OF BOWLING GREEN, OHIO, A CORPORATION.

UNIVERSAL JOINT.

1,265,834.

Specification of Letters Patent.

Patented May 14, 1918.

Application filed October 8, 1917. Serial No. 195,215.

To all whom it may concern:

Be it known that I, BERTIS H. URSCHEL, a citizen of the United States, residing at Bowling Green, in the county of Wood and State of Ohio, have invented certain new and useful Improvements in Universal Joints; and I do declare the following to be a full, clear, and exact description of the invention, such as will enable others skilled 5 in the art to which it appertains to make and use the same, reference being had to the accompanying drawings, and to the letters and figures of reference marked thereon, which form a part of this specification.

10 In the casings, "boots" or housings for universal joints, as usually employed in automobile practice, these casings are of cast metal and necessarily impose a considerable weight and lateral pressure upon the 15 joint. It has been proposed to overcome this difficulty by the use of sheet metal stamped or pressed to the desired form. The use of sheet metal for this purpose has, however, proved unsuccessful for the reason 20 that it lacks sufficient stability to resist the strains to which it is subjected, more particularly at the points where the necessary 25 bolts or rivets are applied.

My invention relates to and its object is 30 to provide a construction which shall overcome the difficulties and objections here indicated, and to furnish a structure which shall be light strong durable and economical as compared with structures of this character heretofore in use.

To these ends my device consists of a 35 universal joint casing an illustrative embodiment of which is hereinafter described, and shown and illustrated in the accompanying drawings, in which—

Figure 1 is a side-elevation of a casing 40 for universal joints with parts broken away to show in section the flange-construction hereinafter referred to, and Fig. 2, a top 45 plan-view of the cup-shaped member hereinafter referred to with its companion piece or cap removed.

Like numerals of reference indicate like 50 parts in both views.

In the drawings, 1 is a cup-shaped member and 2 a cap or closure for the mouth or rim of the cup. These members are provided with the usual or any preferred devices by means of which the casing is oper- 55 atively connected with and supported by

the driving and the driven shafts of a universal joint. The casing may be supplied with any preferred means for retaining the lubricant employed with the joints and these need not be here further illustrated or described. The members 1 and 2 are flanged at their meeting edges or faces as at 5 and the flanges are secured together by means of bolts 3 passing through equi-distant registering holes 4 in the flanges. 60

The opening, not shown, through the member 2 is contracted so that it is adapted to tightly and rigidly clasp one of said shaft-members. The other opening is adapted to be closed by a suitable oil retaining member, which should clasp the other of such shaft-members, the opening 7 being large enough to permit the requisite angular movement of the driving and driven shafts relatively to each other. It will be understood 75 that thus the casing is supported by and revolves with the shafts.

One or both of the members 1—2 is formed of sheet metal of sufficient gage, accurately shaped in appropriate dies to the 80 required form. If the flanges 5 were left of a single thickness it is manifest that they would be distorted and broken in the assembling of the parts and in the use of the device, resulting in disturbing the alinement 85 of the shafts and joint. To obviate this difficulty the flange is at first formed of a single thickness of metal of about twice the width required for the completed flange, and is then turned inwardly and backwardly 90 and doubled upon itself in such fashion as to form a closely pressed double thickness of sheet metal, thus furnishing sufficient stock for the proper retention of the necessary bolts and sufficient strength to resist any 95 strains that may be applied to the parts. It will be seen that the flange thus formed serves as a circumferential rib or brace which lends rigidity to the structure. The circumferential corrugations 6, formed to 100 fit a suitable closure for the shaft opening 7 in the member 1, lend additional rigidity to the sheet metal structure.

Having described my invention, what I claim and desire to secure by Letters Patent, is—

1. A casing for a universal joint, comprising two cup-shaped members pressed or stamped from sheet metal, each having a flanged mouth, the flange consisting of a flat 110

circumferential rim bent backwardly and pressed upon itself to form a double thickness of sheet metal; and means for joining the flanges.

5 2. A casing for a universal joint, comprising a cup-shaped member pressed or stamped from sheet metal and having a flanged mouth, the flange consisting of a flat circumferential rim bent backwardly and 10 pressed upon itself to form a double thickness of sheet metal, combined with another cup-shaped member having a corresponding

flange, and means for rigidly joining said two flanges, said cup-shaped members having—opposite the flanges—openings therethrough, one of said openings being surrounded by a circumferentially corrugated rim. 15

In testimony whereof I affix my signature in presence of two witnesses.

BERTIS H. URSCHEL.

Witnesses:

REASEL ORDWAY,
G. F. GOMERSALL.
